DESIGN FOR A WINDSHIELD DEFROSTING DEVICE

Warren A. Ramsay, Jersey City, N. J.

Application May 3, 1937, Serial No. 69,140

Term of patent 14 years

To all whom it may concern:

Be it known that I, Warren A. Ramsay, a citizen of the United States, residing at Jersey City, in the county of Hudson and State of New Jersey, have invented a new, original, and ornamental Design for a Windshield Defrosting Device, of which the following is a specification, reference being had to the accompanying drawing, forming part thereof.

In the drawing:

Fig. 1 is a perspective view of the windshield defrosting device, showing my new design.

Fig. 2 is a top plan view of the device.

Fig. 3 is a front elevational view thereof; and

Fig. 4 is an enlarged sectional view thru one of the pipe elements forming a part of the device.

I claim:

The ornamental design for a windshield defrosting device, as shown.

WARREN A. RAMSAY.
